UNITED STATES PATENT OFFICE.

JOSEPH STANIS, OF RIVERTON, ILLINOIS.

AIR COMPRESSOR.

1,426,325.

Specification of Letters Patent. Patented Aug. 15, 1922.

Application filed July 11, 1921. Serial No. 484,007.

To all whom it may concern:

Be it known that I, JOSEPH STANIS, formerly a subject of the Czar of Russia, have declared my intention to become a citizen 5 of the United States, as evidenced by the accompanying certificate of the clerk of the United States district court at Springfield, Illinois; that I am now a resident of the town of Riverton, county of Sangamon, 10 and State of Illinois; and that I have invented a new and useful Air Compressor, of which the following is a specification.

The invention relates to transportable air compressors. A prime purpose of the invention is to provide in conjunction with a car for transporting the compressing machine from place to place, a compressing machine operatively connected with a rotating axle of the car, to drive the compressing mechanism. Other purposes of the invention are to provide improved means operable by the car axle to actuate the air compressor; to provide an air compressing machine comprising two batteries of alternately effective cylinders taking filtered air 20 through a single main air duct and in communication with all the cylinders; to provide in conjunction with two batteries of cylinders a single service pipe taking compressed air from all the cylinders and delivering it into a suitable reservoir; to provide a series of compression cylinders in pairs, the two cylinders of a pair being in line with each other, and in conjunction therewith to provide a series of simultaneously operating walking beams in such relation to the cylinders that each walking beam will simultaneously operate the pistons of one pair of cylinders; to provide positive 30 means for selective operation of the several walking beams; to provide in conjunction with a series of walking beams a corresponding series of cams adjustable relatively to the respective walking beams; to provide improved means for lubricating the respective cams; to provide means for filtering the air entering the main air duct; to provide in conjunction with chain-driven air-compressing mechanism a tension device 40 automatically controlling the tension of the driving chain; and to provide other details of construction as will hereinafter appear.

The invention is illustrated in the annexed drawings to which reference is hereby

made, and will now be described in detail 55 and the novel features thereof will be recited in the appended claims.

Figure 1 is a side elevation of an air compressor embodying my invention, installed on an ordinary flat car and shows, in elevation, a locomotive for pulling the car; Fig. 2 is a vertical transverse section on the line 2—2 of Fig. 1; Fig. 3 is a horizontal longitudinal section through the air compressor taken on the line 3—3 of Fig. 1; 60 Fig. 4 is an enlarged top plan of the device for controlling the tension of the main drive chain; Fig. 5 is a vertical longitudinal section on the line 5—5 of Fig. 4; Fig. 6 is an enlarged vertical section through one 65 cylinder taken on the line 6—6 of Fig. 3; and Fig. 7 is an enlarged sectional view of the filter at the upper end of the intake pipe.

The same reference numerals designate 70 the same parts in all the views. The car 6 and its axle 7 are of usual construction and need not be described. A sprocket wheel 8 fixed on the rotating axle 7 carries the main drive-chain 9 which actuates the air compressing devices as will hereinafter appear. 75 A rectangular frame 10, preferably of cast iron is supported on the car 6. A deck 12 extends upwardly from the frame 10 and supports two parallel series of grease cans 13 which contain what is known as hard 80 grease. At the lower end of each can is a brush of candlewick 14 (Fig. 2) extending 85 upwardly into the grease in the box and wiping the grease on the face of cams which rotate under the respective cans. Within 90 the frame 10 are two batteries of cylinders 15. The cylinders of one battery are in line 95 with the respective cylinders of the other battery. In the present instance there are four cylinders in each battery, but a battery may comprise a greater or a less number of cylinders without departure from my invention. Each cylinder comprises an inwardly opening intake valve 16 (Fig. 6) and 100 an outwardly opening outlet valve 17. Pistons 18 slide in the respective cylinders 15. Air is drawn into the cylinders during upward movement of the pistons and is compressed during downward movement of the pistons. An upright intake pipe 19 (Fig. 1) 105 communicates with branches 20 (Fig. 3) which have laterals 21 in communication with the respective cylinders 15. A conical

filter box 22 at the upper end of the intake pipe 19 has a removable perforated bottom 57 (Fig. 7) through which air is admitted and contains fibrous material 58 for filtering the air. The admitted air flows upwardly through the box 22, downwardly through the pipe 19, and through the branches 20 and the laterals 21 into the respective cylinders 15. An outlet pipe 23 10 communicates with branches 24 which in turn communicate with the interior of the respective cylinders 15. A main drive shaft 25 rotates in suitable bearings on the main frame. A sprocket wheel 26 adjacent to 15 one end of the shaft is loose on the main shaft and a pulley 51 is fixed at the other end of the same shaft. A smaller sprocket wheel 27 is integral with the wheel 26. A driven shaft 28 is parallel to the shaft 25 20 and is rotative in suitable bearings on the main frame. A sprocket chain 29 connects the wheels 27 and 55. The main chain 9 drives the wheel 26 and the chain 29 drives the wheel 55. The wheel 26 has also a clutch member 30 which is engaged by a clutch member 31 sliding on the shaft 25. The member 31 has a circumferential groove in which the fork 32 of a lever 33 fulcrumed on the main frame engages to slide the 25 clutch member 31 on the shaft. A spring 34 (Fig. 2) acts on the clutch member 31 to slide it inwardly and normally keep it engaged with the clutch member 30. To disengage the clutch members 30 and 31 the upper end of the lever 33 will be pulled outwardly. A series of cams 35 are fixed on the shaft 25 and a similar series of cams 36 in line with the cams 35 are connected with the shaft 28. A series of walking beams 37 40 spaced apart from each other by tubular spacers 38 oscillate on a transverse shaft 39 supported by the upright members 40 of the frame 10.

I have shown and described an apparatus 45 comprising four walking beams and four pairs of cylinders but it is obvious that a greater or less number of walking beams and a greater or less number of pairs of cylinders may be used without departure from 50 my invention.

A reservoir 41 stationary on the car receives compressed air coming through the outlet pipe 23.

A service pipe 42 in communication with 55 the interior of the reservoir through a valve 59, conveys compressed air from the reservoir to the place where it is to be used and the valve controls the flow of air through the pipe.

To keep the main drive-chain under 60 proper tension for satisfactory operation of the apparatus an automatic tightener is provided. The tightener structure will now be described. Transverse bars 43 (Figs. 4 and 65 5) are fixed on the underside of the car floor.

Longitudinal guide rails 44, parallel to each other, are fixed on the underside of the bars 43. Rectangular frames 45 are free to slide on the rails 44. Each frame 45 carries a rotative sheave 46 in line with the chain 9. 70 The chain 9 travels in a longitudinal slot 47 in the car floor. There are two springs 48. Each spring connects one frame 45 with one bar 43 and the springs act to pull the frames away from each other. The downward run 75 of the chain 9 is on the outside of one sheave 46 and its upward run is on the outside of the other sheave and the springs act to cause the sheaves to maintain uniform stress on both runs, and thereby take up any slack of 80 the chain.

A valve 49 communicating with the interior of the reservoir 41 may be used to control communication with the usual reservoir 54 on the locomotive, which supplies compressed air in the usual pipe line of the train. 85

A suitable gauge 50 communicating with the interior of the reservoir 41 indicates the air pressure in the reservoir. 90

A gasoline engine 52 of any usual or approved construction is bolted on the floor of the car and actuates a belt 53 to drive the pulley 51 which is fixed on the main shaft 25. In case the air pressure in the reservoir 95 41 runs low while the car is at rest the engine 52 will be used to operate the compressor to force additional air into the reservoir to properly increase the air pressure therein. 100

In practice the car on which the compressing apparatus is installed will be drawn from place to place by the locomotive A.

Forward movement of the car will cause rotation of the axle 7, causing the chain 9 to drive the gear 26 which in turn will drive the main shaft 25 to simultaneously rotate all the cams 35; and the chain 29, running on the sprocket wheels 27 and 55, will drive the shaft 28 to simultaneously rotate all 110 the cams 36. The axes of the cams 35 and 36 are eccentric to the respective shafts 25 and 28, and are set on the shafts in such manner that when the cams on one shaft are at the highest point of their orbits the cams 115 on the other shaft will be at the lowest points of their orbits, and the peripheries of the cams will run in contact with the upper surfaces of the walking beams, in order that when one end of the beam descends to make 120 the downward stroke of the piston at that end of the beam, the other end of the beam will ascend and will pull upward the piston in the opposite cylinder; and so on for every walking beam. At the highest point 125 of rotation of each cam the surface of the cam will engage the corresponding wick brush 14 which will apply grease on the contacting surface of the cam.

Having fully described my invention what 130

I claim as new and desire to secure by Letters Patent is:

1. In an apparatus of the class described the combination of a propellible vehicle having a rotative axle; a sprocket wheel fixed on said axle; a double series of compression cylinders on said vehicle; pistons sliding in the respective cylinders; a rotative main drive shaft in operative relation to said cylinders; a sprocket wheel loose on said shaft; a sliding clutch-member rotating with said shaft and engaging said loose sprocket wheel; piston-operating devices actuated by said main drive shaft; a drive chain connecting the sprocket wheel on the axle with the sprocket wheel on the main drive shaft; and spring-controlled sheaves pulling on the upward run and on the downward run of drive chain to maintain uniform tension of the chain.
2. In an air compressor, the combination of a series of pairs of compressor cylinders and pistons co-acting with the respective cylinders; a series of walking beams, each operating one pair of pistons; a rotative first shaft; a second shaft rotating in unison with said first shaft; a series of cams on said first shaft, each cam acting to depress one member of the respective walking beams; and a series of cams on said second shaft, each cam of said last named series acting to depress the other member of the respective walking beams.

In witness whereof I have hereunto signed my name at Riverton, Illinois, this 5 day of July, 1921.

JOSEPH STANIS.
